SURPRINTING

William J. Wilkinson, Eastchester, N. Y., assignor
of one-half to Miehle Printing Press and Man-
ufacturing Company, a corporation of Illinois

Application January 12, 1937, Serial No. 120,249

24 Claims. (Cl. 95—5)

The present invention pertains to certain features of improvement and betterment in the surprinting of typematter, lettering, or the like, either with colorless type or in one or more colors, 5 in combination with associated illustrations or comparable matter.

One aim of the invention is to provide a new procedure of this kind which is economical to practice, which may be followed with comparative ease and dispatch, and which affords results 10 of the highest and most acceptable grade, including precise registration.

To enable those acquainted with this art to understand the principles underlying the invention, and, in order that the latter may be practised with various styles of printing, several desirable and preferred embodiments of the invention have been illustrated in the accompanying drawings which should be considered in connection 20 with the following detailed description. In these drawings:

Figure 1 depicts the method of surprinting colorless typematter;

Figure 2 portrays the procedure when the lettering is printed in colors;

Figure 3 sets forth the process when lettering is printed in one color and dropped out of another in registered relation.

The procedures in Figures 1, 2 and 3 all relate 30 to deep-etch offset-printing.

Figure 4 outlines the surprinting in colorless type in connection with intaglio printing employing a hemi-tone positive, by which is meant a positive in which all tones are one-half of their 35 value in the original subject, used for the production of the printing plate; and

Figure 5 presents the method used in the same general procedure for surprinting in colors.

In all figures of the drawings the emulsion side 40 of the element is shown as being uppermost.

Referring first to Figure 1, it will be observed that a reverse-negative 11 is made from the original subject or copy 10 and from such negative a bichromated glue or gelatin positive 12 on glass is 45 produced and developed by water in accordance with the well-known and established practice, and such positive is dyed in methyl-violet-solution in the customary manner that a copper print is dyed for photoengraving, this dyeing permitting the 50 extent of development to be made readily apparent and making the subject visible in the positive, such dyeing, however, not modifying the light-transmitting properties of the positive, which from a photographic standpoint is transparent.

55 Those acquainted with this art will, of course, understand that the reverse-negative referred to is made either by having the glass of the light-sensitive plate toward the lens, or by making the negative through a glass-prism.

60 A stripping-negative 13 is made of the separate

black typematter or lettering 14 to be surprinted and such negative is stripped from its support and applied on the positive 12 with the typematter in the desired position with relation to the visible, but photographically non-printing, subject-matter of such positive, and any portions of the latter not properly covered by the negative and desired to be covered are opaqued by hand in any approved manner, this duplex, master, non-printing positive and its adhered negative being 10 designated by the reference numeral 15.

Thereupon the reverse-negative 11, after having been coated on its gelatin side with bichromated-glue, preferably with a coating of waterproof collodion between such coating and the negative, is registered with the master member 15 using the customary registration marks for that purpose, and exposed to light therethrough and then water-developed in the usual way, after which it is dyed with a concentrated methyl-violet-solution and then rendered photographically opaque as to its light exposed portions by a solution of iodine in a weak solution of potassium iodide, thus producing, after washing and drying, the element 16 comprising a combination of 20 the original subject coupled with the desired associated typematter.

Hereinafter, in this application, where surprinting on a light-sensitive bichromated-glue coating is referred to, the complete process is 30 meant, namely, exposure of such coating to light through the master, developing with water in the usual manner, dyeing with a concentrated methyl-violet-solution, treating with a solution of iodine in a weak solution of potassium iodide, 35 washing and drying.

From the member 16 a half-tone positive 17 is made and this is used to provide a light-exposed and developed resist coating 18 on the metal-plate which is etched therethrough in the usual way, 40 this printing plate printing the original subject correctly and also printing the typematter in colorless type in correct position, as will be readily understood from what precedes.

If the original subject is in colors and is to 45 be printed in like colors and it is desired to have the lettering printed in colorless type on the final print, then each color-separation reverse-negative is treated in the same way as referred to above, under which circumstances, each color 50 printing-plate will print the typematter in colorless type, the like typematters of all of the plates printing in exact register with one another.

It is, of course, to be understood that the single master-plate 15 is used with each of the several 55 color-separation reverse-negatives; or stated in other words, it is not necessary to make a member 15 for each such negative.

In case the lettering or typematter is to be 60 printed in one or more colors, the procedure

shown in Figure 2 is followed, in which instance, a color-separation reverse-negative 21 is made from the original subject or copy 22 for each color to be used in printing the typematter and then 5 the following method is practiced for each such color.

A reverse-negative 23 is made of the subject, a stripping-negative 24 is made of the typematter 25, and then negative 24 is stripped from its support and mounted on the reverse-negative 23 in proper position for the typematter thereon, the emulsion of negative 23 having been previously scraped off clean from the proper area or areas, this compound negative 26 being opaqued as may 10 be required so that only the lettering will be surprinted.

A half-tone positive 27 is made from the reverse-negative 21 and then on a bichromated-glue coating applied to such positive, the double 20 negative 26 is surprinted, giving, when completed, the positive 28 which is then applied to, and printed through onto, the resist 29 on the metal-plate or cylinder, which of course after suitable development is etched in appropriate manner.

Each color-separation negative treated in this way will result in the typematter being printed in its color, so that any single color or combination of colors may be used for such lettering, it being understood that only one such double or 30 master negative 26 need be made and used in the stated manner successively with the half-tone positives required to produce the desired result.

Colors of the copy not involved in the surprinting have their printing-plates made in the 35 usual way, the surprinting, of course, being omitted, so that in the final print the original is in its proper colors and the lettering is in its selected one or more colors.

As another example, assume, for instance, that 40 it is desired that the typematter or lettering be printed in certain colors and dropped out of another color or colors appearing in the original, such a plan is depicted in detail in Figure 3.

In this case, orange-colored lettering is to appear 45 in the final print of the copy and obviously such lettering must be carried by the yellow and red printing-plates to provide the orange color, but the copy presents a blue area in which such orange lettering must appear, and the lettering 50 must be dropped entirely out from the blue and black printing-plates, this whole procedure, of course, calling for exceedingly close and precise register.

In carrying out this process, reverse development 55 may be resorted to with advantage, by which is meant that method of known development whereby a positive may be made directly from a positive or a negative from a negative, in which case, however, the negative produced 60 would be a reverse of the original negative.

Assuming that the original copy 31 has an illustration 32 in colors and a blue area 33 in which latter the typematter or lettering in the final print is to appear in orange color, from such copy 65 a red-separation reverse-negative 34 is made as is also a blue-separation reverse-negative 35, and a methyl-violet-solution-dyed, bichromated-glue positive 36 is made from the blue-separation reverse-negative 35, in the manner specified above 70 in connection with Figure 1.

A stripping-negative 37 is made from the typematter copy 38 and it is stripped onto positive 36 in proper position with relation to the zone corresponding to the colored area 33 of the original 75 copy, whereupon the remainder of the positive

36 is opaqued by hand, thereby producing a duplex-member 39, the subject-matter of which is surprinted on the blue-separation reverse-negative 35 after the latter has been coated with collodion and on top of that coated with the usual 5 light-impressionable bichromated-glue, thereby making member 40, and from such negative 40 a half-tone positive 41 is made which is used to provide the corresponding, photographic, developed, screened resist 42 on the metal-plate 10 which, of course, is etched in the usual way through such resist.

Obviously, this surprinted, blue-separation printing-plate will print in blue and will leave the spaces for the lettering on the blue area 15 clear; or, in other words, the lettering will be colorless.

A half-tone positive 43 is made from the red-separation reverse-negative 34 and the subject-matter of a reverse-developed, preferably, but not necessarily super-contrast, negative 44, made from the master 39, is surprinted on a light-sensitive bichromated-glue coating applied on the screened positive 43, producing the member 45, the latter being used to light-affect the resist 46 applied to 25 the surface of the red printing-plate, the plate being etched in the customary manner through such resist after its development. Obviously, this red printing-plate will print the illustration and the lettering in red.

The corresponding yellow-separation reverse-negative is treated in the same way, including the use of the master negative 44 to provide a yellow printing-plate which will print the illustration in yellow and the lettering in yellow.

A black printing-plate is made in the usual way.

Thus all four color-separation printing-plates will print the illustration in their individual colors to collectively or unitedly provide a print corresponding to the original copy.

The blue printing-plate will supply the lettering in the print colorless, cutting it out of the original blue area of the copy and leaving it colorless.

Both the red and yellow printing-plates, however, print the lettering in exact register with the colorless spaces or lettering left by the blue printing plate, whereby the final lettering is orange, surrounded by the remainder of the blue area.

In intaglio printing a process involving a printing-plate having the tones of the design or illustration represented at approximately one-half of their true values and with the darkest shadows of the plate comprising separated ink-wells, the 55 walls of which afford adequate support for the doctor-blade, has been developed and the present invention may also be used in the manner indicated in Figures 4 and 5 in conformity with such procedure.

If the lettering or typematter is to be printed colorless in the print, the method in Figure 4 is employed; whereas, if it is to be in one or more colors, the process set forth in Figure 5 is resorted to.

Referring first to the operation of Figure 4, an ordinary photographic negative 51 is made of the original subject or copy 52 and from such negative a methyl-violet-solution-dyed glue-print positive 53 is made on glass in the manner here- 70 before mentioned.

A stripping-negative 54 having been made from the separate type-matter 55, it is removed from its support and affixed in proper position on the positive 53 and the resulting double member 75

opaqued as needed, thereby producing a master, duplex, dyed positive-and-negative 56.

Negative 51 having been coated with a light-responsive bichromated-glue facing, with an intervening collodion-coating, has the subject-matter of member 56 surprinted thereon, thus providing the surprinted negative 57 from which a so-called hemitone, screened positive 58 is made, and this is photographically printed on the light-sensitive resist-coating 59 applied to the surface of the metal-plate which is to form the printing element.

After such plate has been etched through the developed resist and used as a printing-plate or cylinder, it will be apparent that the original subject will appear properly on the print and the colorless lettering will be correctly associated therewith.

If the subject or copy is to be reproduced or duplicated in its original colors, each color-separation negative, corresponding to negative 51, will have the typematter surprinted thereon by means of the successive use of the single master-element 56.

In the colored print the lettering will have been printed colorless because it will have been eliminated in the manner indicated from all of the color printing-plates.

On the other hand, in the event that the lettering is to be in one or more colors, then the practice suggested in Figure 5 is followed, wherein a negative 61 is made of the original copy 62, another negative 63 is made of the same copy, and a stripping-negative 64 of the typematter or lettering 65 is stripped on negative 63 and opaqued as needed, thereby producing the dual or two-fold master-negative 66, the emulsion being scraped clean on negative 63 before applying the stripped negative 64 as may be needed to provide proper area or areas for the lettering.

From negative 61 a hemi-tone, screened positive 67 is made through a suitable screen with appropriate screen-distance and exposure, whereupon by a hereinbefore-specified bichromated-glue coating superposed on such positive 67, the subject-matter of the master duplex negative 66 is surprinted thereon, an appropriate screen being stripped on to the master duplex negative 66 over the typematter so that in the resulting surprinted positive 68 both the illustration and the typematter appear as screened, this being required for proper support of the doctor-blade by the printing-plate to be made therefrom.

Positive 68 is then light-printed on the resist on the metal-plate and the resist when developed will appear as at 69, and, of course, the plate is etched as usual to form the printing-element.

If such printing-plate is printed with one color, the illustration and lettering will conformably appear in the print in the same single color.

In case the original copy is in colors and is to be so duplicated in the print, obviously, each such color-separation hemi-tone positive 67 made from the corresponding color-separation negative 61 will be surprinted from the single or common master 66 in the manner already indicated as would be required to produce the lettering in the needed color or colors.

On the other hand, if the original copy had a colored area in which lettering of a different color or colors was to appear, then the original color or colors would have to be cut out analogously to the procedure presented in Figure 3.

Those acquainted with this art will readily know what changes to incorporate in the de-

scribed processes to get similar or different results, as, for instance, the manner of application of the present invention to letter-press printing would present no material obstacles to one versed in the art.

Whereas hereinbefore the surprinting of typematter has been referred to, it is to be understood that instead of typematter any desirable designs, images, pictures, etc. may be thus surprinted, inserted or added in like or analogous manner.

Also modifications of the procedures set forth above may be resorted to without departure from the heart and essence of the invention as defined by the appended claims and without the loss or sacrifice of any of its material benefits.

It is to be understood that on the master additional stripping may be done so as to add tone, Ben Days, etc.

As shown in the various figures of the drawings, the typematter or lettering is intentionally separated from the illustration, for purposes of clarity, but as will be readily understood, such lettering or typematter may be located directly in or on a vari-colored illustration.

The methyl violet solution hereinbefore referred to may be of any suitable strength as is well-known in the art, and in the practice of this process it may be practically or actually saturated.

As to the iodine solution, it is well-known that iodine is insoluble in water but is soluble in a weak solution of either iodide or bromide of potassium, and since the iodides and bromides are relatively expensive, a weak solution can be used to advantage and satisfaction.

I claim:

1. In the method of surprinting supplemental matter for the production of a printing-plate, the steps of making a stripping-transparency of the original supplemental matter, making a transparency of the original copy, stripping said supplemental-matter-transparency and securing it in proper position on said copy-transparency, thereby providing a supplemental-matter-master, opaquing said master, if not otherwise opaque, except for said supplemental matter, and supplying a photographic opposite of said master on a transparency of the original copy, said opposite being photographically-opaque in those portions thereof which have been acted upon by the light through said master.

2. In the method of surprinting supplemental matter for the production of printing-plates, the steps of making a stripping-transparency of the original supplemental matter, making a transparency of the original copy, stripping said supplemental-matter transparency and securing it in proper position on said copy-transparency, thereby providing a supplemental-matter-master, opaquing said master, if not otherwise opaque, except for said supplemental matter, and supplying to each of a plurality of color-separation transparencies of the original copy a photographic-opposite of said master, said opposite being photographically opaque in those positions thereof which have been acted upon by light through said master.

3. In the method of surprinting supplemental matter for the production of a printing-plate, the steps of making a stripping-transparency of the original supplemental matter, making a transparency of the original copy, stripping said supplemental-matter-transparency and securing it in proper position on said copy-transparency, thereby providing a supplemental-matter-master, opaquing said master, if not otherwise

- opaque, except for said supplemental matter, coating a second transparency of the original copy with a light-sensitive stratum, photographically surprising said master on and developing 5 said stratum, and rendering the light-exposed portions of said developed coating photographically opaque.
4. In the method of surprising supplemental matter for the production of printing-plates, 10 the steps of making a stripping-transparency of the original supplemental matter, making a transparency of the original copy, stripping said supplemental-matter-transparency and securing it in proper position on said copy-transparency, 15 thereby providing a supplemental-matter-master, opaques said master, if not otherwise opaque, except for said supplemental matter, coating each of a plurality of color-separation transparencies of the original copy with a light- 20 sensitive stratum, photographically surprising said master on and developing each of said strata, and rendering the light-exposed portions of said developed coatings photographically opaque.
- 25 5. The method presented in claim 3 in which said light-sensitive stratum is bichromated-glue and separated from the underlying transparency by a waterproof-coating.
6. The method presented in claim 4 in which each of said light-sensitive strata is bichromated- 10 glue and separated from the underlying transparency by a waterproof-coating.
7. The method presented in claim 3 in which said supplemental-matter-transparency is a negative of the original supplemental matter.
8. The method presented in claim 4 in which said supplemental-matter-transparency is a negative of the original supplemental matter.
9. The method presented in claim 3 in which said copy-transparency is a glue-print positive of the original copy.
10. The method presented in claim 4 in which each of said copy-transparencies is a glue-print positive of the original copy.
11. The method presented in claim 3 in which said copy-transparency is a negative of the original copy.
12. The method presented in claim 3 in which said original copy-transparency is a reverse-negative of the original copy.
13. The method presented in claim 3 in which said light-sensitive stratum is bichromated-glue and separated from the underlying transparency by a waterproof-coating, in which said supplemental-matter-transparency is a negative of the original supplemental matter, and in which said copy-transparency is a glue-print positive of the original copy.
14. The method presented in claim 3 in which said light-sensitive stratum is bichromated-glue and separated from the underlying transparency by a waterproof-coating, in which said supplemental-matter-transparency is a negative of the original supplemental-matter, and in which said original copy-transparency is a negative of the original copy.
15. The method presented in claim 3 in which said light-sensitive stratum is bichromated-glue and separated from the underlying transparency by a waterproof-coating, in which said supplemental-matter-transparency is a negative of the original supplemental-matter, and in which said original copy-transparency is a reverse-negative of the original copy.
16. The method presented in claim 4 in which each of said color-separation transparencies is a negative of the original copy.
17. The method presented in claim 4 in which each of said color-separation transparencies is 5 a reverse-negative of the original copy.
18. The method presented in claim 4 in which each of said color-separation transparencies is a screened-positive of the original copy.
19. The method presented in claim 4 in which 10 each of said color-separation transparencies is a screened-positive of the original copy and in which said stripping-transparency of the supplemental matter is screened.
20. The method presented in claim 4 in which 15 said supplemental-matter-transparency is a negative of the original supplemental matter, in which each of said color-separation transparencies is a negative of the original copy, and in which each of said light-sensitive strata is bichromated-glue and is separated from the underlying negative by a waterproof-coating.
21. The method presented in claim 4 in which 20 each of said color-separation transparencies is a reverse-negative of the original copy, in which 25 said supplemental-matter-transparency is a negative of the original supplemental matter, and in which each of said light-sensitive strata is bichromated-glue and separated from the underlying reverse-negative by a waterproof-coat- 30 ing.
22. The method presented in claim 4 in which each of said color-separation transparencies is a screened-positive of the original copy, in which 35 said supplemental-matter transparency is a negative of the original supplemental-matter, and in which each of said light-sensitive strata is bichromated-glue and separated from the underlying positive by a waterproof-coating.
23. In the method of surprising supplemental 40 matter for the production of printing-plates, the steps of making a plurality of color-separation transparencies of the copy, making a stripping negative of the supplemental matter, making a dyed glue-print positive of the copy, stripping 45 said negative and applying it in proper position on said positive, opaques the remainder of said positive if necessary, thereby providing a duplex first master, photographically making a second master from said first master by the process of 50 reversal-development, surprising said first master on one or more of said color-separation transparencies, and surprising said second master on the remainder of said color-separation transparencies.
24. In the method of surprising supplemental 55 matter for the production of a printing-plate, the steps of making a stripping-transparency of the original supplemental matter, making a transparency of the original copy, stripping said supplemental-matter-transparency and securing it in proper position on said copy-transparency, thereby providing a supplemental-matter-master opaques said master, if required, except for said supplemental matter, coating a transparency of the original copy with light-sensitive bichromated-glue, exposing said coating to light through said master, water-developing said exposed coating, dyeing said developed coating with a methyl-violet-solution, rendering photographically opaque the light-exposed portions of said coating with an iodine solution, and washing and drying said coating.

WILLIAM J. WILKINSON.
